CHARLES HOLLOWAY, JR., OF SAN FRANCISCO, CALIFORNIA.

PLASTERING STAPLE.

Application filed November 19, 1924. Serial No. 750,865.

To all whom it may concern:

Be it known that I, CHARLES HOLLOWAY, Jr., a citizen of the United States, and a resident of San Francisco, county of San Francisco, State of California, have invented a new and useful Plastering Staple, of which the following is a specification.

This invention relates to stapling devices as used for holding the building paper 10 against a sheathed wall to be plastered and which are at the same time adapted to function as laths or furring strips for spacing the plaster receiving wire mesh away from the paper or sheathing.

15 The objects of the invention are to provide an improved staple of this character which will have the following advantages: More easily held in place by a workman when applying the staple; will drive fair at the blow of a hammer with no tendency to tip; holds the paper tightly the entire length of the strip; affords a flat grip which cannot entrap the fingers in driving; presents both driving points clear of the hand 25 for striking with a hammer; is applicable to long high clearance strips with intermediate staple points; preserves a definite spacing for the mesh even if struck on top with a hammer in securing the mesh with independent nails alongside the staples; cannot 30 interlock in kegs as can wire devices previously used.

The above features are realized in the 35 staple construction shown in the accompanying drawings and in which:

Figure 1 is a side elevation of one form of my staple drawn approximately full size as adapted for ordinary usage;

40 Figure 2 is a bottom view of the device shown in Figure 1;

Figure 3 shows a half staple made according to my invention;

45 Figure 4 shows in plan my method of forming the staple so that both driving points are clear of the holder's hand;

Figure 5 shows a portion of a very large 50 staple embodying my improved features and showing intermediate points and wiring notches;

Figure 6 is a diagram showing the way 55 my staples are cut from the strip of flat metal to form the points and the manner in which the tapered ends are bent to bring the points central for proper driving;

Figure 7 is a reduced sketch showing a

staple held by the left hand with ends presented for driving by a hammer.

In more detail my staple comprises a flat strip of metal 1 of a width corresponding to the desired furring clearance and preferably with the sharp edges rounded so that handling them will not cut a workman's fingers.

The ends 2 of the strip are cut at an angle terminating in sharp points 3 and adjacent the tapered ends the strip is given a quarter twist as at 4 and the tapered ends bent at right angles thereto so as to direct the points in the plane of the flat strip and with the points disposed at the centerline of the strip, as indicated by the dotted line in Figure 2.

To thus bring the points to the centerline, reference is directed to Figure 6 showing the method of cutting and bending the ends, and in which drawing the supply strip of metal 1' is cut off at the desired angle "A" and the tapered end 2 instead of being bent up at right angles to the run of the strip is bent up along an angular line B so that the point 3 will fall on the medial line and not on the right hand edge of the strip as would otherwise be the case.

Also to be observed, is the fact that the quarter twist 4 given the strip is not a free 85 twist which would centralize the twisted portion with the run of the strip but the twisted ends are offset or forced downward so as to bring the flat under surface 5 in line with the under edge 6 of the vertically arranged run or body of the strip, and whereby the device when driven home will firmly seat itself against the paper for the entire distance between the points.

In Figure 3 I show my single pointed 90 strips which are substantially one half of the strip shown in Figure 1.

In Figure 5 a large strip is shown with an intermediate point at 3' struck out of the metal as indicated, and having also notches 100 7 and holes 8 adapted to pass a wire for securing the plastering mesh across the upper edge of the strip.

In applying the straight staples as shown in Figures 1 and 2 the strip is grasped flatwise between the thumb and index finger of the left hand as indicated in Figure 7 and preferably twisted slightly so as to expose both ends clear of the hand for driving with a hammer.

In the modification shown in Figure 4 the ends are both offset to the right as shown so that in holding the device against the wall with the left hand the driving points will always extend some distance from the hand and thereby facilitate driving each end with a single hard blow without danger of hitting the fingers.

In contemplating my staple it should be observed that I do not claim to be the inventor of a staple per se for I am aware of prior devices of this character made of wire and over which my device has the specific advantages enumerated and desired to be covered by the appended claims.

I claim:

1. A plastering staple comprising a flat section strip of metal having the end portion twisted to a plane at right angles to the plane of the strip and formed to lie with one flat side in line with one edge of the strip,

and a point formed on the twisted end extending in the plane of the strip substantially at right angles to the run of the strip.

2. A plastering staple comprising a flat strip of metal having both end portions twisted to lie at right angles to the plane of the strip and both formed with one flat side in line with a common edge of the strip, and a point formed on each twisted end extending therefrom in the plane of the body of the strip substantially at right angles to the run of the strip.

3. A plastering staple comprising a flat strip of metal having both end portions twisted to lie at right angles to the plane of the strip and provided with angularly disposed points, the said strip being curved throughout so as to laterally offset the intermediate portion thereof with respect to said points.

CHARLES HOLLOWAY, JR.
